WASHING MACHINE AGITATOR

Charles C. Scheele, Syracuse, N. Y., assignor to
 Easy Washing Machine Corporation, Syracuse,
 N. Y., a corporation of Delaware

Application June 10, 1941, Serial No. 397,451

2 Claims. (Cl. 68—134)

My invention relates to improvements in an agitator or dolly for a washing machine.

An object of my invention is to provide an agitator, simple in design and easy to manufacture, but effective in operation.

Another object of my invention is to provide an agitator that may be made of molded plastic in a simple mold or die.

A still further object of my invention is to provide an agitator for a washing machine that will exert an unequal thrust in opposite directions on the washing fluid and clothes being washed, when the agitator is oscillated back and forth.

Another object of my invention is to provide an agitator for a washing machine having symmetrically disposed blades so constructed that when the agitator is rotated in one direction the blades create greater turbulence in the washing fluid than when the agitator is rotated in the opposite direction.

Another object of my invention is to provide an agitator for a washing machine, said agitator being adapted for oscillation about a vertical axis and being so constructed and arranged that rotation in one direction thrusts the washing fluid and clothes outward and upward.

Further objects and advantages of my invention will become apparent from reading the following specification in connection with the annexed drawings in which:

Figure 1 is a plan view of the agitator of my invention.

Figure 2 is a side elevation of the agitator shown in Figure 1.

Figure 3 is a perspective view, parts being broken away, showing in a wooden pattern, the flat planes defining the various side surfaces of the blades and the base.

Figure 4 is a plan view of a modified agitator showing four blades instead of three.

Figure 5 is a side view or elevation of the agitator shown in Figure 4.

The agitator of my invention comprises a circular base 10, a central column 11 rising vertically from the base to a height corresponding substantially to the normal height of washing fluid in the washing machine vat, and a plurality of blades 12 extending outwardly from the column 11 to the periphery 13 of the base 10. In the preferred form shown in Figure 1 the central column 11 is triangular in cross-section and the blades 12 are three in number. Extending upwardly from the under side of the base 10 into the column 11 is a non-circular socket 11' adapted to receive the end of the agitator supporting shaft 55

(not shown) which is oscillated by suitable mechanism (not shown).

The blades extend outwardly from the central polyhedron or column 11 so that one side 14 of each blade forms an extension of a side of the central column. The opposite side 15 of the blade 12 intersects the central column 11 so that the side 14 is longer than the side 15, as seen best in Figure 1. The sides 14 and 15 are straight and parallel to, although offset from, a radius of the base. The wooden pattern of Figure 3 clearly indicates that the sides 14 and 15 of each blade are straight, that is they have no curvature in horizontal plane. The upper surface 20 of the base 10 is formed of a plurality of planes equal to the number of blades. Each plane is horizontal in the direction of the short side of a blade, as indicated by the line 21 in Figure 3. Each plane, however, slopes upwardly from the periphery 13 of the base 10 as the plane extends from the outer edge of the long side of a blade to the intersection with the short side of an adjacent blade, as indicated by the line 22 on Figure 3. The blades 12 are all of substantially the same height and in the preferred form extend upwardly from the base approximately one-third of the total height of the agitator. It will be noted on examining Figure 2 that the long side 14 of the blade 12, is deeper at the outer edge of the blade, as shown at 23, than is the corresponding short side 15 of the same blade, which merges with the base plane along the line 21. The intersection between all meeting planes is in each case rounded out with a fillet. However, the fillet along the junction line 21 is of much larger radius than the fillet along the junction line 22. In the modification shown in Figures 4 and 5, the same plan of construction is used for a four-bladed agitator as distinguished from the three-bladed agitator shown in Figures 1, 2 and 3. The same reference numerals are used on Figures 4 and 5, as the only difference between the two agitators lies in the number of blades and the shape of the central column, which is triangular in the three-bladed agitator and square in the case of the four-bladed agitator.

Due to the fact that the paddle portion of each blade 12 has a greater depth on the side 14 than on the side 15, when the agitator is oscillated in a washing machine, a greater vortex and greater turbulence is created on the deep side 14 of the blade 12 than on the shallow side 15. Furthermore, due to the fact that the upper surface of the base slopes downwardly away from the shallow side of the blade, there is a certain stream-

lining effect on this side of the blade. For example, when the agitator shown in Figure 1 is oscillated clockwise, the vortex behind the blade will cause the fluid to follow the blade. When the agitator is oscillated in the opposite direction there is likewise a vortex created behind the blade, but this vortex will be of lesser violence and through the sloping of the base will tend to slide off so the tendency to draw the fluid behind the blade is less. Thus with a greater tendency to move the fluid clockwise than counter-clockwise when the agitator is oscillated back and forth, there is a resultant circulation of varying velocity around the vat in a clockwise direction. This action is further assisted by the offset location of the blades. The upward sloping of the base planes, from the points 23 to intersection line 24, effects the fluid flow by thrusting the fluid and clothes upward on the clockwise portion of an oscillation, thus assisting the roll-over action of the clothes and aiding in the more rapid and thorough washing of the clothes.

I claim:

1. A washing machine agitator comprising a substantially circular base, a plurality of symmetrical, flat blades of substantially uniform thickness extending vertically from said base, said blades being parallel to and offset in the same direction from one of a like number of symmetrically disposed reference radii of said base, said blades intersecting adjacent the center of the agitator to form a prismatic central column the respective faces of which constitute extensions of one side surface of each blade, whereby each of said blades is wider on one side than on the other, each of said blades being deeper on its

wider side than on its other side, each of the segments of said base between adjacent blades having its upper surface lying in a plane that is substantially horizontal in the direction of the shallow side of a boundary blade and sloping in the direction of the deep side of the other boundary blade, and means for mounting said agitator to oscillate about the axis of its central column.

2. A washing machine agitator comprising a substantially circular base, a plurality of symmetrical, flat blades of substantially uniform thickness extending vertically from said base, said blades being parallel to and offset in the same direction from one of a like number of symmetrically disposed reference radii of said base, said blades intersecting adjacent the center of the agitator to form a prismatic central column the respective faces of which constitute extensions of one side surface of each blade, whereby each of said blades is wider on one side than on the other, each of said blades being deeper on its wider side than on its other side, each of the segments of said base between adjacent blades having its upper surface lying in a plane that is substantially horizontal in the direction of the shallow side of a boundary blade and sloping in the direction of the deep side of the other boundary blade, each of said blades extending vertically approximately one-third of the total height of said agitator and extending outward substantially to the periphery of said base, the upper edges of said blades sloping downward toward said central column, and means for mounting said agitator to oscillate about the axis of its central column.

CHARLES C. SCHEELE.
